Specification of Letters Patent.

Patented Jan. 1, 1918.

Original application filed December 18, 1916, Serial No. 137,491. Divided and this application filed May 29, 1917. Serial No. 171,676.

To all whom it may concern:

Be it known that we, WILLIAM J. HAMPTON and WILLIAM H. RITTS, citizens of the United States, and residents of Pittsburgh and Etna, respectively, in the county of Allegheny and State of Pennsylvania, have invented a new and useful Improvement in Rolling-Mills; and we do hereby declare the following to be a full, clear, and exact 10 description thereof.

Our invention pertains to rolling mills, that is, to mills comprising a plurality of rolls through which a billet of steel is passed successively, thereby to form said billet into 15 an elongated plate or sheet.

This application is a division of our co-pending application, Serial Number 137,491, filed December 18, 1916, for improvements in rolling mills.

20 Rolling mills of the kind referred to, as now in use, generally consist of a plurality of sets of rolls, there being usually three of such sets, generally known as the "roughing" rolls, the "strand" rolls, and the "finishing" rolls. The set of roughing rolls ordinarily comprises three rolls disposed one above the other, these rolls usually having a plurality of passes arranged one beside the other. In some instances, the strand rolls 25 have two or four passes, one above the other. In other instances, the strand rolls have an odd number of passes, depending upon the ultimate direction which it is desired that the billet shall take. Usually, the billet is 30

first carried through the pass between the bottom roughing roll and the center roughing roll, and is then carried back through the pass between the center roughing roll and the upper roughing roll; it is then 35

40 carried back through a pass, arranged beside the first pass, between the bottom roughing roll and the center roughing roll, and then back through a similar pass between the center roughing roll and the top roughing

45 roll. The four passes between the roughing rolls may be sufficient; but sometimes a billet may go through six passes of these rolls. From the roughing rolls the partly rolled plate is transferred to the strand rolls;

50 and it is carried to and fro between these rolls, in the same way as in the case of the roughing rolls. The nearly finished plate is then transferred to the finishing rolls,

through which it is passed once, and then carried on to a suitable shearing device or 55 the like.

It is an object of the present invention to improve generally upon rolling mills broadly of the type referred to above.

It is a further object of the invention to 60 provide an improved means for transferring the billet from a position in which it has just gone through an upper pass of the rolls into a position from which it may go through a lower pass of the rolls. 65

It is a still further object of the invention generally to provide improved means for transferring the billet from the upper passes of any one set of rolls to a lower pass of the same and for transferring it from one 70 set of rolls to another.

And other and further objects of the invention will appear from the following specification taken in connection with the claims annexed thereto. 75

A rolling mill constructed in accordance with our invention is described, by way of example, in the following specification and is shown in the accompanying drawings. It is especially to be understood, however, 80 that the invention may be embodied in other forms, and that changes may be made in the form described and shown, without exceeding the scope thereof, as defined in the appended claims. 85

In the drawings:

Figure 1 is a plan of a rolling mill constructed in accordance with our invention;

Fig. 2 is a partial section, on an enlarged scale, taken on the line 2—2 of Fig. 1, looking in the direction of the arrows; 90

Fig. 3 is a partial section, on an enlarged scale, taken on the line 3—3 of Fig. 4, looking in the direction of the arrows;

Fig. 4 is a partial transverse section, on an enlarged scale, taken on the lines 4—4 of Figs. 1 and 3, looking in the direction of the arrows; and 95

Fig. 5 is a partial section, on an enlarged scale, taken on the line 5—5 of Fig. 1, looking in the direction of the arrows. 100

Like reference characters refer to like parts throughout the following specification and the several figures of the accompanying drawing.

105 Referring now particularly to Figs. 1, 2

and 5, A indicates the roughing rolls, supported in the ordinary bearings, and rotated in the usual manner. In the embodiment of our invention now being described, 5 there are three of these roughing rolls, A', A² and A³, respectively. These rolls are formed with three sets of passes, which are indicated on the drawings as a, b, and c, each 10 set comprising an upper pass and a lower pass. The upper pass c is more constricted than the lower pass a, which latter, in turn, is more constricted than the upper pass b. The passes become, in turn, less constricted, until the lower pass a is reached, which is 15 the least constricted of all. It will be seen that as a billet is carried forward through the lower pass a, backward through the upper pass a, forward through the lower pass b, backward through the upper pass b, forward 20 through the lower pass c, and backward through the upper pass c, it will be rolled out to a lesser thickness at each pass. Upon leaving the roughing rolls, the partly rolled plate is transferred to the strand rolls 25 B. These strand rolls B comprise three rolls B', B², and B³. In the embodiment now being described the strand rolls are formed with two sets of passes, d and e, each set comprising an upper and a lower pass. The 30 upper pass d is more constricted than the lower pass d; but the passes e are identical with the passes d, so as to permit the passes e to be used when the rolls are worn at the passes d. The passage of the partly finished 35 plate forward through the lower pass d, and backward through the upper pass d, further elongates the plate and further reduces its thickness. The plate is then transferred to the finishing rolls, which consist 40 of a pair of rolls C disposed one above the other, the plate simply passing forward between these rolls.

At the front side of the machine,—i. e., at the side from which the billet first enters 45 the rolls,—a plurality of feed rolls 10 are mounted upon a suitable supporting structure. These rolls are continuously rotated by a suitable motor and gearing, indicated at 11, such as those heretofore in use in mills 50 of this character. The billet f is removed from the furnace and placed upon the rotating rolls 10, which carry it forward to the lower pass a of the roughing rolls A, the billet being thus seized between the roughing rolls A' and A², and carried through the 55 same, thereby making its first pass.

On the rearward side of the machine there are provided three forwarding rolls 12, 13 and 14 respectively (Fig. 2), which rotate in the 60 same direction as the rolls 10. The roll 12 is placed on a higher plane than the roughing roll A², the roll 13 being likewise placed on a higher plane than the roll 12, and the roll 14 being placed on a higher plane than 65 the roll 13. Thus the rolls 12, 13 and 14,

together with inclined intermediate shelves 12^a and 13^a, placed between them, form an inclined guide, up which the billet is carried after passing between the roughing rolls A' and A². Beyond the forwarding rolls 12, 13 and 14 are placed three returning rolls 15, 16 and 17 respectively, which are rotated in the opposite direction to that of the forwarding rolls. The rolls 15, 16 and 17 are arranged in the same horizontal plane with 75 each other; and a continuation of this plane is formed by a table 18 which has adjustably mounted thereon a support 19 for a spring buffer 20. Placed above the forwarding rolls 12 and 13 are two further returning 80 rolls 21 and 22. The returning rolls 21 and 22 rotate in the same direction as the returning rolls 15, 16 and 17, but are placed upon a higher plane than these last. A shelf 23 is disposed between the returning rolls 21 and 85 22; and a guide roll 24 is placed immediately in front of the roll 21. The returning rolls 21 and 22, the shelf 23, and the guide roll 24, are all mounted upon a standard 25 suitably supported from the main structure. 90

After the billet f makes its first pass, through the lower pass a between the roughing rolls A', its front end is carried onto the forwarding roll 12, and thence over the shelf 12^a, onto the forwarding roll 13. These 95 rolls, with the forwarding roll 14, carry the billet forward in an upwardly inclined direction. Thus the billet will reach a position such as that indicated in full lines in Fig. 2. After the billet has been moved farther from the position shown in Fig. 2, its uppermost end will overbalance its lowermost end, permitting its uppermost end to fall upon the returning rolls 15, 16 and 17. The momentum of the billet will carry it 100 forward until it strikes the resilient buffer 20, which will give the billet an impulse in the return direction. The returning rolls 15, 16 and 17, rotating in a direction opposite to that of the forwarding rolls, will cause 110 the billet to move back over the path that it has already traversed, until its end strikes the guide roll 24. (See dotted line position, Fig. 2). When the billet strikes the guide roll 24, its front end is directed upwardly 115 onto the returning roll 21. The billet f is thus carried upward onto the returning rolls 21 and 22, and is thereby directed into the upper pass a, between the roughing rolls A' and A², thereby making its second pass. 120

After being carried through the upper pass a, between the roughing rolls A' and A², the billet f is received upon a transferring device 26 (Figs. 1, 3 and 4). This transferring device consists of a plurality of 125 feet 27, which are secured, by bolts 28, in transverse grooves 29 formed in a plurality of shelves 30, one of which shelves is disposed between each pair of the feed-rolls 10. The connection of the feet 27 with the 130

shelves 30 is such as to permit of transverse adjustment of the feet with respect to the shelves. Connecting between the feet is an elongated web 31, from which extends upwardly and outwardly an inclined slideway-portion 32. A horizontal shelf-portion 33 projects outwardly from the upper part of the slideway-portion 32, and terminates in a vertical guide portion 34.

As the billet *f* emerges from the upper pass *a* between the roughing rolls *A'* and *A³*, having made its second pass, its front end comes upon the shelf portion 33 of the transferring device 26, as shown in full lines in Fig. 4. The shelf portion 33 is less in width than one-half the width of the billet *f*; so that when the billet has become freed from the roughing rolls, it will fall into the position indicated in dotted lines in Fig. 4, and will thence slide down the slideway-portion 32 onto the feed rolls 10. The billet is thus transferred from the plane of the upper passes of the roughing rolls to the plane of the lower passes of the latter. The upright web 31 of the transferring device 26 also serves as a guide for properly directing the billet, prior to its first pass, into the lower pass *a*.

Upon falling from the transferring device 26 onto the feed rolls 10, the billet is fed forward by these continuously rotating rolls, and is thus directed into the lower pass *b* between the roughing rolls *A'* and *A²*. Upon being carried through the rolls, thus making its third pass, the billet again rides up the forwarding rolls 12, 13 and 14, overbalances, falls upon the returning rolls 15, 16 and 17, and strikes a second resilient buffer 35 on the table 18, the buffer 35 being situated farther back than the buffer 20, to allow for the increased length of the billet. The buffer 35 gives a returning impulse to the billet, which latter is then carried backward by the returning rolls 15, 16 and 17 onto the returning rolls 21 and 22, which latter feed the billet into the upper pass *b*, between the roughing rolls *A'* and *A³*.

Upon emerging from the rolls, having thus made its fourth pass, the billet comes onto a transferring device 26^a, which is of a similar construction to the transferring device 26, and includes an upright web 31^a, a slideway-portion 32^a, a shelf portion 33^a, and a guide portion 34^a. The transferring device 26^a is longer than the transferring device 26, to accommodate the increased length of the billet. In the manner which has been described above in connection with the transferring device 26, the billet is again transferred to the feed rolls 10. The web portion 31^a of the transferring device 26^a forms a guide for properly directing the billet, in its third pass, into the lower pass *b*. Likewise, the guide portion 34^a of the transferring device 26^a operates as a guide for the billet

during its emergence, on its second pass, from the upper pass *a*.

Upon the billet *f* being delivered, by the transferring device 26^a, to the continuously rotating feed rolls 10, it is fed, by these rolls, to the lower pass *c*, between the roughing rolls *A'* and *A²*. The billet is carried through the rolls, thus making its fifth pass. Although still referred to, for convenience, as a billet, the metal has now assumed the shape of an elongated and relatively thin sheet. The billet, in this form, does not have the stiffness which it had in its original shorter form; and it is not desirable further solely to rely upon its mere lying on the forwarding and returning rolls for effecting its forwarding and return movement. For greater certainty of action, therefore, pinch-rolls are provided for moving the billet after the same has emerged from its fifth pass.

The pinch-rolls associated with the roughing rolls are shown in Fig. 2. They consist of rolls 36 and 37, mounted one at each end of a balance arm 38. The balance arm 38 is rockably mounted, at its center, on a shaft 39 carried by a stand 40 suitably mounted on the main structure. Suitable mechanical means consisting of a steam cylinder having a slide valve 45 and piston 46 and suitable connections are provided for rocking the pinch-rolls to cause engagement with the billet.

Upon the billet *f* being transferred, from the transferring device 26^a, to the continuously rotating feed rolls 10, these latter present it to the lower pass *c*, between the roughing rolls *A'* and *A²*. The billet is carried through these rolls, thereby making its fifth pass, and rides up the forwarding rolls 12, 13 and 14. As soon as the front end of the billet reaches the forwarding roll 14, the rocking mechanism is operated to cause the pinch-roll 36 to descend upon the billet and hold it firmly against such forwarding roll. The forwarding roll 14, with the billet thus forcibly clamped against it, is able thereafter to continue the forwarding movement of the billet. As soon as the rear end of the billet reaches the pinch-roll 36, the rocking mechanism is operated to cause the pinch-roll 37 to descend upon the billet and hold it firmly against the returning roll 16. When this happens, the returning roll 16, having the billet thus firmly clamped against it, will cause the latter to move in the opposite direction and be carried up onto the returning rolls 21 and 22. The returning rolls 21 and 22 present the billet to the upper pass *c*, between the roughing rolls *A'* and *A³*, between which rolls it is carried, thereby completing its sixth pass.

As the billet emerges from the upper pass *c*, between the roughing rolls *A'* and *A³*, it is received upon a table 50, the latter being

supported upon the ends of a plurality of transverse rails 51. These rails 51 are carried by a pair of I-beams 52, supported by the main structure. The table 50 is provided 5 along its edge with an upright guide 53, which serves to guide the billet as it comes out from the upper pass *c*, and also serves to guide the opposite edge of the billet as it comes out from the upper pass *b* on completing 10 its fourth pass.

When the billet reaches the table 50, the operations upon it have been completed, so far as the roughing rolls are concerned. The billet has the form of an elongated, relatively 15 thin strip, which, being white hot, is quite flexible. The operations of the roughing rolls have been described as consisting of six passes. However, this may be varied. For instance, only four passes may be used, 20 the billet being carried twice to and fro between the roughing rolls. When only four passes are used, the pinch-rolls will ordinarily be employed prior to the fourth pass.

The rails 51 extend across the machine 25 from the roughing rolls A to the strand rolls B. These rails terminate in downwardly inclined portions 54, forming a sloping surface, the lower ends of these downwardly inclined portions 54 terminating at a feed 30 table 55 placed in the front of the strand rolls B. Extending diagonally across one side of the machine, at the end of the receiving table 50, is a plate 56 having, at its outer edge, an upwardly-extending guide 57. 35 After the billet has come out onto the receiving table 50, from the upper pass *c* of the roughing rolls, it is manually pulled across the rails 51 and allowed to slide down the slope formed by the inclined portions 54. 40 In this way the billet is brought onto the feed table 55 for the strand rolls. The inclined guide wall 57 of the plate 56 assists in this transfer.

A longitudinal guide 57^a is provided upon 45 the feed table 55, and is placed in such a position that when the billet is pulled against it, the billet will be in proper position for entering the lower pass *d* between the strand rolls B' and B². The top surface of a feed 50 roll 58 extends through the feed table 55, this feed roll rotating in such a direction as to cause the billet to be moved toward the strand rolls. With the feed roll 58 co-operates a pinch-roll 59 which is moved down, to 55 press the billet against the roll 58, as soon as the billet is brought into position upon the feed table 55. As soon as the billet has been brought upon the feed table 55, and the pinch roll 59 has been operated, to force the 60 billet into close engagement with the feed roll 58, this latter roll causes the billet to move forward into the lower pass *d*, between the strand rolls B' and B². The billet is then carried through these strand rolls, thus effecting the seventh pass.

Upon being carried through the lower pass *d* of the strand rolls, the billet emerges upon an upwardly inclined table 60. Beyond the end of the table 60 there are provided a forwarding roll 62 and a pair of returning rolls 70 63 and 64. With the forwarding roll 62 and the returning roll 64 co-operate a pair of pinch-rolls 65 and 66, the same being mounted upon a balance arm 67, which is operated by a device which is similar to the device 75 described in connection with pinch-rolls 36 and 37, the same being controlled by an operating lever 68, placed beside the operating lever 49 so that the same workman can attend to the operation of both levers. 80 Hingedly connected with a transverse shelf 69 connected across the uprights of the frame work of the strand rolls B is a chute plate 70. This chute plate is flared outwardly from its upper to its lower end and is provided with upwardly extending side members 71, thereby properly to receive the billet, in the return movement of the latter, and direct it to the upper pass *d* between the strand rolls B' and B². Likewise the table 85 90 95 60 is provided with an upright guide 72 for directing the billet properly to and from the pinch rolls.

As the billet comes out onto the table 60, and as soon as its end reaches the forwarding rolls 62, the workman operates the lever 68 in such a way as to cause the pinch roll 65 to descend upon the billet and grip it firmly against the forwarding roll 62. In coming to the forwarding roll 62, the billet 10 forces its way under the chute plate 70, lifting the latter somewhat about its pivot, in its hinged connection with plate or shelf 69. When the rear end of the billet has passed beyond the end of the chute plate 70, 10 10 10 the workman operates the lever 68 in such a way as to cause the pinch roll 66 to grip the billet against the returning roll 64, whereby a reversal of the direction of movement of the billet is effected. Upon this 11 11 11 reversal of movement taking place, the billet travels back again down the table 61, but, when moving in the new direction, its end rides up the chute plate 70 and is thereby directed to the upper pass *d* between the 115 strand rolls B' and B². The billet is then carried through these strand rolls, thereby effecting its eighth pass.

In order to permit the second pair of 120 passes *e* to be used in place of the first pair of passes *d*, when the latter become worn, the chute plate 70 is mounted upon the support 69, in such a manner that it can be easily moved from one side of such support, in which it co-operates with the passes *d* of 125 the strand rolls, to the other side of the support, in which it co-operates with the passes *e* of the strand rolls. The guides 57^a and 72 are likewise movable; and the pinch rolls 65 and 66 are wide enough to accommodate 130

the billet through whichever pair of passes it is being carried. When the passes *d* become worn, all that is necessary is to shift the guides 57^a and 72, and move the chute 5 plate 70 to the other side of the support 69. As the billet emerges from the upper pass *d* of the strand rolls, it comes upon a table 73 which extends diagonally across the machine from a position in line with the strand 10 rolls to a position in line with the finishing rolls C. This table is of a sectional nature and is provided with a vertical guide flange 74 along its inner edge. Extending from the table 73 are transverse rails 75, terminating in inclined portions 76, these rails being of a similar nature to the rails 51, with their inclined portions 54, described above. The inclined portions 76 of the rails 15 75 terminate upon a feed table 77 which is disposed in alignment with the finishing 20 rolls C.

Upon the billet, now in the form of a very long and very thin plate, emerging from the upper pass *d* onto the table 73 it 25 is manually pulled across the rails 75 and down the inclined portions 76, onto the feed table 77. The upper surface of the feed roll 58 projects through the table 77 in the same way as it projects through the table 30 55, and with this feed roll coöperates a pinch roll 78, which may be brought down into engagement with the billet to press the latter against the feed roll. When the pinch roll 78 is thus brought into engagement with 35 the billet, the feed roll moves the billet forward between the finishing rolls C, through which it is carried, thus making the ninth pass. Upon emerging from the finishing rolls C, the billet comes upon a roller table 40 79, from which it is carried to a suitable shearing device.

The means for operating the pinch rolls 59 and 78 is as follows: The pinch roll 78 is mounted upon an arm 80, carried by a 45 rockable shaft connected by suitable steam operating mechanism 81 with a lever 82. The pinch roll 59 is operated by a suitable mechanism and is connected to a lever 83.

The rolling mill described above is particularly 50 advantageous in that it permits of a continuous movement of the billet from the time the latter is placed onto the original feed rolls until after it passes the finishing rolls. Special elevating devices, requiring 55 to be operated individually for each billet, for lifting the billet from the plane of the lower rolls to the plane of the upper rolls, are done away with; and in this way the speed at which the machine can operate is 60 greatly increased. Likewise, the necessity of personal supervision at the various stages of the operation is considerably reduced. A further advantage of the device is that the 65 jolting of the billets, especially at the times when they fall from the upper plane to the

lower plane, owing to the action of the transferring devices 26 and 26^a results in a loosening of the scale permitting the scale to fall away from the billets to a large extent.

Having thus fully described our invention, what we claim as new and desire to secure by Letters Patent is:—

1. A rolling mill comprising a set of rolls arranged so as to present a plurality of passes, some of said passes being above other 75 of said passes, and a transferring device for bringing the article being rolled from an upper pass to a lower pass, said transferring device comprising a shelf of less width than the article being rolled, whereby, when said 80 article comes upon said shelf, it falls therefrom after being released by said rolls.

2. A rolling mill comprising a set of rolls arranged so as to present a plurality of passes, some of said passes being above other 85 of said passes, and a transferring device for bringing the article being rolled from the plane of an upper pass to the plane of a lower pass, said transferring device comprising a shelf of less width than the article being 90 rolled and an inclined portion depending from said shelf, for the purposes set forth.

3. A rolling mill comprising a set of rolls, disposed so as to present a plurality of passes, some of said passes being above other 95 of said passes, a transferring device for bringing the article being rolled from the plane of an upper pass to the plane of a lower pass, said transferring device including a shelf of less width than the article being 100 rolled, and feed rolls for receiving said article from said transferring device.

4. A rolling mill comprising a set of rolls arranged so as to present a plurality of passes, some of said passes being above other 105 of said passes, a transferring device for moving the article being rolled from the plane of an upper pass to the plane of a lower pass, said transferring device including a shelf of less width than the article being 110 rolled, and an inclined portion depending from said shelf and a feed roll for receiving said article from said transferring device.

5. In a rolling mill having rolls arranged 115 so as to present a plurality of passes, some of said passes being above other of said passes, a transferring device for bringing an article being rolled from an upper pass to a lower pass, said transferring device comprising a shelf of less width than the article being rolled, and a slideway portion depending from said shelf.

6. In a rolling mill having rolls arranged so as to present a plurality of passes, some of 125 said passes being above other of said passes, a transferring device for bringing the article being rolled from an upper pass to a lower pass, said transferring device comprising a shelf portion having a vertical guide por- 130

6
tion, and an inclined slideway-portion depending from said shelf.

7. In a rolling mill, an adjustably mounted transferring device for bringing the article being rolled from the upper pass to the lower pass, said device comprising a shelf portion having a guide portion thereon, a slideway portion depending from said shelf, and a base portion.
- 10 8. A transferring device for rolling mills comprising a shelf portion, a vertical guide portion, an inclined slideway-portion de-

pending from said shelf, and a base portion, all of said parts being integral.

In testimony whereof, we, the said WIL-¹⁶ LIAM J. HAMPTON and WILLIAM H. RITTS, have hereunto set our hands.

WILLIAM J. HAMPTON.
